UNITED STATES PATENT OFFICE.

WILFRED SHURTLEFF, OF MOLINE, ILLINOIS, ASSIGNOR TO DION GERALDINE, OF CHICAGO, ILLINOIS.

MASSAGING APPARATUS.

1,274,799.

Specification of Letters Patent.

Patented Aug. 6, 1918.

Application filed August 20, 1914, Serial No. 857,679. Renewed January 12, 1918. Serial No. 211,675.

To all whom it may concern:

Be it known that I, WILFRED SHURTLEFF, a citizen of the United States, and resident of Moline, in the county of Rock Island and 5 State of Illinois, have made certain new and useful Improvements in Massaging Apparatus, of which the following is a specification.

This invention relates to a massaging apparatus which may be either mechanically 10 operated or the desired effect may be obtained by the designed movements of the patient.

An object of the present invention is to provide a massaging apparatus including a 15 plurality of centrally projecting pivotally mounted or yieldable arms upon the extremities of which are mounted massaging rollers adapted to bear against the patient and produce the desired kneading or massaging effect thereon, by effecting relative reciprocation of said rollers and the support upon which the patient is sustained, or by properly directed contortions of the patient's body. In the illustrated instance 20 the support is a platform constituting a part of the machine but may be otherwise.

A further object is to provide a massaging apparatus including a plurality of centrally projecting pivotally mounted arms with 25 suitably shaped rollers at their extremities which are arranged in relative staggered relation to thus engage the patient's body at contiguous points and press continually thereagainst, following the contour thereof.

30 Suitable means are provided for varying the pressure with which the massaging rollers engage the patient and also the parts of the body treated. In the illustrated embodiment of the invention a reciprocating platform is employed upon which the patient is supported, thus resulting in the movement of the massaging rollers over the patient's body, at the same time producing a vibratory and stimulating, as well as a 35 healing effect, over the entire body of the patient.

With the foregoing and other objects in view which will appear as the description proceeds, the invention resides in the combination and arrangement of parts and in the details of construction hereinafter described and claimed, it being understood 40 that changes in the precise embodiment of the invention herein disclosed, can be made

within the scope of what is claimed, without 55 departing from the spirit of the invention.

In the drawings accompanying this specification and forming a part thereof, the preferred embodiment of my invention is illustrated, wherein:—

Figure 1 is a view in side elevation of my improved massaging apparatus with a portion of the driving mechanism of the reciprocating platform illustrated in section and diagrammatically illustrating a patient 65 in operable position within the apparatus.

Fig. 2 is a cross sectional view taken on the line 2—2 of Fig. 1.

Fig. 3 is a detail view of one of the massaging arms and illustrating, in section, the 70 adjustable weight whereby the pressure of contact of the rollers is varied.

Fig. 4 is a somewhat modified form in which a spring exerts the requisite inward force to the massaging rollers.

Referring to the drawings in which similar reference numerals designate corresponding parts throughout the several views, a base 5 rigidly supports the upright columns or guide posts 6 which are provided at their upper extremities with the cross members 7, thus providing for their mutual support and reinforcement.

The platform 8 is provided with suitable polygonal apertures 9 extending therethrough which slidably receive the posts 6 therein and thus restrict the platform to a vertical reciprocating motion. The platform is reciprocated or vibrated by means of the cam shafts 10 which are rotatably 85 supported upon the foundation base 5 and are equipped with the cams 11 which contact with and support the platform 8. A power driven shaft 12 is adapted to mechanically rotate the cam shafts 10 through 90 the instrumentality of the beveled gears 13, the speed of rotation of the cam shafts depending upon the treatment to be applied to the patient's body.

Slidably mounted upon the polygonal 100 posts 6 are the brackets 14, the same including the centrally disposed sockets 15 slidably mounted upon the posts and adjustably held thereto by means of the set screws 16. Each bracket supports, at its opposite and 105 remote extremities the arms 17 and 18, the same being mounted for pivotal motion and allowing the arms to move inwardly to fol-

low the contour of the patient's body. The various arms which are of two different lengths, are provided at their upper portions with the hooked extremities 20 through 5 which the trunnions 21 of the parabolic rollers 22 extend. The curved surfaces of these rollers define a substantially circular band adapted to engage, upon all sides, a patient's body and massage the same, the continuity 10 of the surfaces being illustrated in Fig. 2. Each bracket carries an arm of each length, thus arranging the rollers in staggered relation and preventing any interference therebetween which would in any way tend to 15 restrict their independent motions.

The arms are provided at their lower extremities with the offset portions 17' and 18' through which the pins 19 extend and from which extend projections 23. The arms, 20 when taken in connection with these projections define a plurality of bell crank levers upon the lower projecting portions 23 of which are adjustably mounted the weights 24, provided with suitable locking means 25. 25 The weights are thus adapted to force the arms inward against the patient's body with a pressure that may be adjusted and varied as desired. The modified form of bell crank lever illustrated in Fig. 4 includes the aper-tured projection 26 to which the retractile spring 27 is secured, the lower extremity of 30 which is adjustably secured to the finger which depends from the bracket.

The vibratory motion imparted to the 35 platform will impart a similar movement to the patient's body and render the same more susceptible to the massaging contacting members or rollers 22. The adjustability of the various brackets allows the massaging 40 members to engage the patient's body at any desired locality. The vibrations or movements of the platform result in the relative movement of the patient's body and the massaging rollers, thus producing the desired 45 effect and the reduction of the fatty tissues. The arms are inclined inwardly and upwardly and completely encircle the patient's body. Due to the inward force imparted to the arms by means of either the weights or 50 retractile springs, the arms follow the contour of the patient's body and remain in continuous contact therewith. It will be evident that the platform is in effect a support for the patient or for the patient's 55 limbs to be massaged.

Having thus fully described my invention, what I claim is:

1. In an apparatus of the class described, the combination of a patient supporting reciprocating platform, and a plurality of massaging contacting members mounted in a group about the platform for movement in a substantially horizontal plane radially with respect to the center of such group. 60

65 2. In a massaging apparatus, the combina-

tion of a platform, means for vibrating the same and a plurality of massage contacting members movable laterally with respect to said platform and held against movement substantially in the direction of the vibrat-ing motion of the platform. 70

3. In an apparatus of the class described, the combination of a patient supporting reciprocating platform, a plurality of pivoted arms projecting centrally and upwardly 75 with respect to said platform and massaging members located at the upper extremities of said arms.

4. In an apparatus of the class described, the combination of a vertically movable plat-form, means engaging and adapted to recipro-cate the same, and a plurality of massag-ing members mounted for horizontal motion and held against vertical motion, and means adapted to move the same laterally 80 with respect to said platform to continu-ously contact with a patient's body. 85

5. An apparatus of the class described, comprising a plurality of upright posts ar-ranged about an imaginary axis, arms pivot-ally secured at their lower extremities and supported by said posts, and projecting in-wardly and upwardly from their supports, and massaging members arranged in stag-90 gered relation carried at the upper extremi-ties of said arms and arranged to form a group around the said axis above the plat-form. 95

6. A massaging apparatus comprising posts arranged to inclose a space, brackets 100 adjustably mounted thereon, and a plurality of arms pivotally secured at their lower ex-tremities to said brackets and projecting up-wardly and inwardly therefrom with re-spect to the space inclosed by said posts and 105 massaging contact members carried at the upper extremities of said arms.

7. A massaging apparatus comprising posts arranged to inclose a space, brackets 110 adjustable mounted thereon, a plurality of arms pivotally secured at their lower ex-tremities to said brackets and projecting up-wardly and inwardly therefrom with respect to the space inclosed by said posts, massag-ing contact members carried at the upper ex-tremities of said arms, and means engaging 115 said arms adapted to move the same inward to hold the massaging members in continu-ous contact with the surface of the body.

8. A massaging apparatus comprising a 120 plurality of brackets arranged to inclose a space, means supporting the same for ad-justment in a vertical direction, a plurality of massage contacting members carried by 125 said brackets and arranged in staggered re-lation, and means for moving said massage contacting members inwardly toward one another within the space inclosed by said brackets.

9. A massaging apparatus comprising a 130

plurality of pivotally mounted arms extending upwardly and inwardly within the space inclosed by the pivotal mountings of said arms, and curved massaging rollers carried 5 at the upper extremities thereof, arranged in staggered relation, and adapted to engage a patient's body at contiguous points.

10. A massaging apparatus comprising a plurality of spaced posts, brackets including 10 central sockets adjustably mounted upon said posts and projecting to the sides thereof, unequal arms pivotally secured to the bracket extremities, said arms provided with upper hook-shaped ends, and massaging 15 members carried at the upper extremities of said arms.

11. A massaging apparatus comprising a plurality of spaced posts, brackets including 20 central sockets adjustably mounted upon said posts and projecting to the sides thereof, unequal arms pivotally secured to the bracket extremities, said arms provided with upper hook-shaped ends, massaging members carried at the upper extremities of said 25 arms, and means engaging said arms adapted to move the massaging members one toward the other and maintain the same in continuous contact with a patient's body.

12. A massaging apparatus comprising a 30 plurality of spaced posts, brackets including a central socket adjustably mounted upon said posts and projecting to the sides thereof, unequal arms pivotally secured to the bracket extremities, said arms provided with 35 upper hook-shaped ends, massaging members carried at the upper extremities of said arms, means engaging said arms adapted to move the massaging members one toward the other and maintain the same in continuous 40 contact with a patient's body and at adjustable pressures.

13. A massaging apparatus comprising a 45 plurality of spaced posts, a platform slidably mounted thereon, means engaging said platform adapted to vibrate the same in a vertical direction, a plurality of brackets slidably mounted upon said posts, means for locking said brackets in adjusted positions, a plurality of unequal arms pivotally secured to the extremities of said brackets and 50 provided with upper hook-shaped ends ex-

tending inwardly toward one another above the axis of the platform, a plurality of curved massaging rollers carried at the hooked extremities of said arms and adapted 55 to encompass and continuously contact with a patient's body.

14. In a massaging apparatus the combination of a patient supporting reciprocating platform, means for reciprocating the same, 60 a plurality of massage contacting members held against movement in the direction of the reciprocatory motion of the platform and mounted for movement one toward the other to embrace and engage at contiguous 65 points the patient mounted upon said platform.

15. In a massaging apparatus the combination of a patient supporting reciprocating platform, means for reciprocating the 70 same, and a plurality of parabolic massage contacting members.

16. A massaging apparatus comprising a plurality of substantially parabolic massaging rollers, means mounting the same for 75 movement one toward and away from the other, said rollers staggered one above the other and defining a substantially circular band adapted to engage the body at contiguous 80 points.

17. In an apparatus of the class described, the combination with a plurality of massaging contact members mounted in a group about a support for a patient to be treated and adapted for movement inwardly and outwardly with respect to the center of said group, with means for effecting relative reciprocation of the support and contacting 85 members.

18. A massaging apparatus comprising a plurality of massaging rollers, said rollers being staggered, one out of line with the others, and defining a substantially inclosing band adapted to engage the body of the patient at contiguous points, and means for effecting relative reciprocation of said rollers and a patient supported within said inclosing band. 90 95
